UNITED STATES PATENT OFFICE

151,742

DESIGN FOR A BRASSIÈRE

Lilly Daché, New York, N. Y.

Application March 16, 1948, Serial No. 145,110

Term of patent 14 years

(Cl. D20—4)

To all whom it may concern:

Be it known that I, Lilly Daché, a citizen of the United States, residing at New York, in the county of New York and State of New York, have invented a new, original, and ornamental Design for a Brassière, of which the following is a specification, reference being had to the accompanying drawing, forming part thereof.

In the drawing

Fig. 1 is a front perspective view of a brassière, showing my new design;

Fig. 2 is a rear perspective view thereof.

I claim:

The ornamental design for a brassière, as shown.

LILLY DACHÉ.
